UNITED STATES PATENT OFFICE.

NATHAN SCHWARTZ, OF NEW YORK, N. Y.

GAS-MASK.

1,320,935.

Specification of Letters Patent. Patented Nov. 4, 1919.

Application filed September 13, 1918. Serial No. 253,920.

To all whom it may concern:

Be it known that I, NATHAN SCHWARTZ, a citizen of the United States, and a resident of the city of New York, borough of Manhattan, in the county and State of New York, have invented a new and Improved Gas-Mask, of which the following is a full, clear, and exact description.

The object of the invention is to provide a new and improved gas mask more especially designed for army and industrial use and arranged to enable the user to breathe freely and without danger of inhaling noxious gases with which the surrounding air is charged. Another object is to eliminate dead or exhaled air at the mouth and nose portions of the mask. Another object is to insure proper vision and to prevent noxious gases from reaching the eyes. Another object is to provide a gas mask which can be comfortably worn by a person and which is neat in appearance and not unduly heavy and cumbersome.

With these and other objects in view the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a reduced perspective view of the gas mask worn by a soldier;

Fig. 2 is a sectional side elevation of the gas mask;

Fig. 3 is a reduced plan view of the respirator;

Fig. 4 is a reduced inverted plan view of the respirator; and

Fig. 5 is a reduced sectional plan view of the gas mask along the eye portions.

The body 10 of the gas mask is made of an impervious fabric material, such as a closely woven textile fabric covered on the inner face with rubber, and this body 10 is provided with an upper open portion 11 and a lower tubular portion 12 extending downward and forward, as plainly indicated in Figs. 1 and 2. The upper portion 11 of the body 10 is provided with eye openings 13, the walls of which are engaged by mountings 14, preferably made of rubber, and having their outer portions formed with grooved rings 15 engaged by the marginal

edges of lenses or panes 16 of glass, celluloid or other suitable transparent material. The mountings 14 are integrally connected with each other at the inner side of the mask 60 by an elastic part 17 which normally draws the part 18 of the upper portion 11 and lying between the eye openings 13 into a puckered condition to allow the elastic part 17 to stretch with a view to insure tight 65 fitting of the inner face of the mounting against the face of the wearer around the eyes. It is understood that the elastic part 17 of the mounting is detached from the non-elastic part 18 of the flexible upper portion 11 70 of the body 10, as plainly shown in Fig. 5. The sides of the mountings 14 are provided with integral extensions 19 on which are secured the inner ends of attaching elastic straps 20 extending sidewise and secured by 75 stitches 21 to the side edges of the upper portion 11 of the body 10. The free ends of the attaching straps 20 are adapted to be passed around the wearer's head to be fastened together at the back of the head by 80 suitable fastening devices such as buckles, snap fasteners and the like. By reference to Fig. 5 it will be noticed that the parts 22 of the upper body portion 11 and lying between the openings 13 and the stitches 21 85 are puckered by the fixed ends 19 and the adjacent attached band portions to allow of stretching the ends 19 and the band 20 on drawing the latter tight around the wearer's head thus insuring an exceedingly tight fit 90 of the inner face of the mountings 14 and their extension sides 19 on the face of the wearer around the eyes to prevent gases from reaching the eyes. It is understood that by making the mountings 14 of rubber 95 the lenses or panes 16 can be readily inserted in the rings 15 or removed therefrom in case they are broken to permit of replacing the same by new ones.

Into the tubular portion 12 of the body 100 fits a respirator casing 30 provided with an outer purifying chamber 31 filled with charcoal or similar material 32 charged with a neutralizing chemical for neutralizing the acids in the poisonous gases with which the 105 surrounding air may be charged. Thus charcoal may be charged with a chemical for neutralizing carbon monoxide in the air, such as palladium chlorid or sodium palladium chlorid or similar chemicals may be 110 used according to the nature of the poisonous gases to be encountered at the time.

In order to hold the charcoal 32 in position in the chamber 31 use is made of perforate disks or nettings 35 and 36, of which the netting 35 rests on a perforate bottom 37 5 screwed or otherwise fastened into the lower end of the casing 30. The upper disk or netting 36 rests against a perforate top 38 held in the upper end of the chamber 31. The casing 30 is provided in its upper portion 10 with an inner or a breathing chamber 40 in communication at its bottom, by way of the perforate top 38 and the perforate disk or netting 36, with the top of the chamber 31. The casing 30 is provided at its 15 upper end with an inclined mouth facing 41 adapted to fit around the mouth of the wearer and having an opening 42 for the lips of the mouth and opening into the chamber 40. The top of the casing 30 is provided 20 with a nose facing 45 adapted to fit onto the lower portion of the wearer's nose and joining the upper end of the mouth facing 41. The nose facing 45 is provided with two upwardly extending lugs or plugs 46 spaced 25 apart and adapted to pass into the nostrils of the wearer's nose. The lugs 46 are provided with small openings 47 leading to the chamber 40 to allow breathing through the nose. The lugs 46 are preferably provided with 30 threaded bases 48 which screw in openings 49 formed in the bottom of the facing 45. It will be noticed that by the arrangement described the lugs 46 can be readily removed from the nose facing 45 by unscrewing the 35 bases 48 from the nose facing 45 thus leaving the openings 49 unobstructed for nose breathing purposes. It is understood that by the arrangement described the user can breathe either through the nose or the mouth. 40 Mouth breathing is at times necessary especially when the fumes are very dangerous. In this case a large amount of air is used in breathing and this air can be more readily drawn in through the mouth instead of 45 through the nose and without discomfort to the wearer.

In order to permit a safe escape of the foul or exhaled air from the chamber 40, use is made of an exhaling device 50 having a 50 tubular casing 51 forming an integral part of the casing 30 at the front top portion of the chamber 40. The casing 51 is provided with an opening 52 leading into the chamber 40 and normally closed at the upper end by 55 a valve disk 53 held loosely in a chamber 54 arranged in the top of the casing 51. This chamber 54 is closed by a screw cap 55 and is provided at the sides with openings 56 for the escape of the exhaled air. A spring 60 57 is introduced between the cap 55 and the top of the valve disk 53 to normally hold the latter in closed position in the bottom of the chamber 54 to prevent noxious gases from passing by way of the opening 52 into the chamber 40. It will be noticed that when

the air is exhaled by the wearer of the mask into the chamber 40 then such air can pass through the opening 52 and lift the valve 53 to allow the exhaled air under pressure to pass out through the openings 56. As 70 soon as the pressure within the chamber 40 is reduced the valve 53 closes by the action of its spring 57.

In order to support the tubular portion 12 and the respirator mounted therein from the 75 back of the head of the wearer use is made of two elastic straps 60 attached at their upper ends to the straps 20 and secured near their lower ends by stitches 61 to the side edges of the upper portion 11 of the body 10. 80 The lower ends of each strap 60 is provided with a number of diverging straps 62 sewed or otherwise fastened at their free ends to the sides of the tubular portion 12 of the body 10 at the inner face thereof. It will be noticed 85 that by the arrangement described, the straps 60 are drawn tight on adjusting the straps 20, as previously explained, and consequently the straps 62 exert a pull on the tubular portion 12 to draw the mouth facing 41 firmly 90 in contact with the face portion surrounding the mouth of the wearer, and at the same time the nose portion 45 is drawn tight to contact with the lower portion of the nose to prevent the exhaled or other air from 95 lodging within the body 10 of the mask, and insuring inhalation and exhalation by the mouth or the nose or both by way of the chamber 40.

It will also be noticed that by the use 100 of the perforate disk 36 the charcoal is not liable to be drawn into the chamber 40 and in order to safeguard against any particles of the charcoal reaching the mouth use is made of a deflecting plate 70 arranged within the chamber 40 and extending from the bottom of the mouth portion 41 forwardly and upwardly approximately parallel with but spaced from the top 38 of the purifying chamber 31. It will be noticed that by extending the respirator in a downward or a 105 forward direction it presents no undesirable projection and does not seriously interfere with the wearer using weapons, tools or the like. It will also be noticed that by 110 arranging the respirator in this manner and supporting it directly by the elastic straps 62, 60 and 20 from the back of the head of the wearer all undue strain on the face of the wearer is prevented, and consequently the desired comfort is enjoyed 115 by the user. It will further be noticed that the gas mask is very serviceable for soldiers and other army workers for protection against gas attacks, that is, to prevent the 120 inhalation of poisonous gases, fumes or dust in gas attacks in battle and to protect the eyes against lachrymatory gases that may be used. Further, the mask is exceedingly serviceable for the protection of work- 125 130

ers in the industries in which poisonous fumes, smoke and gases are contained in the surrounding air, and the mask also protects against poisonous and irritating dust by protecting the eyes, nose, mouth, throat and lungs.

In practice, the casing 30 of the respirator is inserted from the inner face of the body 10 and is held in the tubular portion 12 by the outwardly flaring sides of the mouth facing 41 and by the casing 51 of the exhalator extending through an opening in the tubular portion 12, as plainly indicated in the drawings. If desired, the respirator 15 can be readily removed for cleaning or sterilizing purposes, for replacing the charcoal and recharging the latter with a purifying chemical whenever it is necessary to do so.

Having thus described my invention, I claim as new and desire to secure by Letters Patent:—

1. A gas mask, comprising a body of a pliable material, lenses mounted on the upper portion of the said body, and a respirator mounted in the lower portion of the said body, the respirator having a close fitting facing for the mouth and a close fitting facing for the nose.

2. A gas mask, comprising a body of a pliable material, lenses mounted on the upper portion of the said body, and a respirator mounted in the lower portion of the said body, the respirator having a close fitting facing for the mouth and a close fitting facing for the nose, the said respirator having a chamber and openings leading to the said chamber from the said mouth facing and the said nose facing.

3. A gas mask provided with a respirator having a close fitting facing for the mouth of the wearer and a close fitting facing for the nose of the wearer, the said respirator having an outer purifying chamber filled with purifying material and having an inner breathing chamber intermediate the said purifying chamber and the said facings, the latter having openings leading to the said inner breathing chamber.

4. A gas mask provided with a respirator having a purifying chamber and a breathing chamber, the breathing chamber having a close fitting facing for the mouth of the wearer and a close fitting facing for the nose of the wearer, the said mouth facing having an opening leading to the interior of the respirator and the said nose facing having two apertured plugs adapted to extend into the nostrils of the wearer's nose, the said plugs having their opening leading into the interior of the respirator.

5. A gas mask provided with a respirator having a purifying chamber and a breathing chamber, the breathing chamber having an inclined and apertured inner wall to fit

the mouth and a top wall to fit under the nose and having apertured plugs adapted to extend into the nostrils of the nose.

6. A gas mask provided with a respirator having a permanent nose facing adapted to fit the lower portion of the wearer's nose, the nose facing having spaced apertured plugs adapted to extend into the nostrils of the nose, the said plugs being mounted on a common base having a threaded nipple 70 screwing into the bottom of the nose facing.

7. A gas mask provided with a respirator having a close fitting facing for the mouth of the wearer and a close fitting facing for the nose of the wearer, the said respirator 80 having an outer purifying chamber filled with purifying material and having an inner breathing chamber intermediate the said purifying chamber and the said facings, the latter having openings leading to 85 the said inner breathing chamber, and a valved exhaler connected with the said inner chamber to allow escape of the exhaled air.

8. A gas mask provided with a respirator having a casing made of solid material, the 90 casing having an outer purifying chamber filled with an air purifying material and open at its outer end to the atmosphere, the said casing having an inner breathing 95 chamber in communication with the said purifying chamber, the said casing having a close fitting facing for the mouth, and a close fitting facing for the nose, the mouth facing having an opening leading to the said breathing chamber, and the nose facing 100 having two apertured plugs communicating with the breathing chamber and adapted to extend into the nostrils.

9. A gas mask provided with a respirator having a casing made of solid material, the 105 casing having an outer purifying chamber filled with an air purifying material and open at its outer end to the atmosphere, the said casing having an inner breathing 110 chamber in communication with the said purifying chamber, the said casing having a close fitting facing for the lower portion of the nose.

10. A gas mask provided with a respirator having a close fitting facing for the 115 mouth of the wearer and a close fitting facing for the nose of the wearer, the said respirator having an outer purifying chamber filled with purifying material and having an inner breathing chamber intermediate the said purifying chamber and the said facings, the latter having openings leading to the said inner breathing chamber, the said inner breathing chamber having a deflecting member extending outwardly from 120 the lower portion of the mouth facing.

11. A gas mask provided with a body of a flexible material and having spaced eye openings, lenses for the said eye openings and a mounting for the said lenses and at- 130

tached to the said body, the said mounting having an elastic connection between the eye opening and detached from the said body to pucker the portion between the eye 5 openings.

12. A gas mask, comprising a body of an impervious fabric having an open upper eyepiece portion and a tubular lower portion, the said upper portion having eye 10 openings, vision panes in the said eye openings and having elastic mountings, a respirator held in the said tubular body portion, attaching straps adapted to be fastened together and connected with the eyepiece 15 mountings, and respirator attaching straps connected with the said eye connecting straps and provided with diverging straps connected with the corresponding side of the said tubular lower portion.

20 13. A gas mask provided with a body of a flexible material having eye openings and

a lens mounting of elastic material and arranged on the inner face of the said body, the said lens mounting having connected rings fitting the walls of the said eye openings and provided at the outside with grooved flanges, and lenses having their marginal edges fitting into the grooves of the flanges. 25

14. A gas mask provided with a body of 30 a flexible material having eye openings, and a lens mounting of elastic material and arranged on the inner face of the said body, the portion of the lens mounting surrounding the eye openings being attached to the 35 inner face of the said body and the portion between the eye openings and the sides of the mounting being detached from the body, and attaching straps secured to the said sides of the mounting and to the side 40 edges of the said body.

NATHAN SCHWARTZ.
